UNITED STATES PATENT OFFICE.

ALBERT W. PERSON, OF HARVARD, NEBRASKA.

ELECTRIC HEATER.

1,051,967.

Specification of Letters Patent.

Patented Feb. 4, 1913.

Application filed March 11, 1912. Serial No. 683,021.

To all whom it may concern:

Be it known that I, ALBERT W. PERSON, a citizen of the United States, residing at Harvard, in the county of Clay and State of Nebraska, have invented certain new and useful Improvements in Electric Heaters, of which the following is a specification, reference being had to the accompanying drawings.

10 This invention relates to new and useful improvements in electrical heaters and my object is to provide a simple and efficient device of this character which will be most effective for various heating purposes.

15 A further object of the invention resides in providing a device having a base formed of a plastic composition and provided with a plurality of channels or grooves adapted to receive the various heating elements and 20 a still further object resides in providing a base of such material as will withstand temperatures high enough for all practical purposes.

25 A still further object of the invention resides in providing a device which is simple and durable in construction, inexpensive to manufacture and one which will be extremely useful in operation.

With these and other objects in view, the 30 invention consists in the novel features of construction, combination and arrangement of parts as will be hereinafter referred to and more particularly pointed out in the specification and claims.

35 In the accompanying drawings forming a part of this application, Figure 1 is a perspective view of my device. Fig. 2 is a top plan view thereof. Fig. 3 is a vertical section through the same; and Fig. 4 is a top 40 plan view of a slightly modified form of the invention.

In describing my invention, I shall refer to the drawings in which similar reference characters designate corresponding parts 45 throughout the several views and in which—

1 indicates a metallic frame of any suitable size and shape supported by the legs 2, and mounted in the frame 1 is a base 3 formed of a plastic composition. This base 50 is provided with a plurality of parallel grooves or channels 4 which communicate with the front and rear channels 5 and 6 respectively, said latter channels extending at right angles to the first mentioned, each 55 of said channels 4 being adapted to receive therein a heating coil 7. Secured in the

channels 5 and 6 by means of the screws 8 are a plurality of contact plates 9, said plates being arranged at the ends of alternate partition walls for the grooves 4 and each plate being of such length as to be disposed across a pair of adjacent grooves. This permits the ends of the heating coils 7 to be engaged with the plates 9; said coils being held in contact by means of the wood screws 10 and from this construction it will be seen that all of the coils will be placed in the same circuit. The one end of the two outer coils is engaged with an additional contact plate 11 there being two plates in view of the fact that there are two coils and from these plates extend wires 12 and 13 which connect with a pair of terminals 14 and 15. Wires may be engaged with these terminals from the main circuit and as the circuit is completed, the coils will give forth heat for cooking or other purposes.

In order to provide for toasting on this device, I provide a grid plate 16 which is adapted to be secured to the frame 1, said plate being provided with a plurality of slots or channels to align with the slots 4 of the insulating base 3. By arranging the slots in the grid plate so as to align with the longitudinal channels of the composition 85 body, the heat units which radiate from the heating coils 7, may readily pass through said slots to be quickly absorbed by the articles placed on said grid plate. A cover or top plate 17 is also provided, which may be 90 readily removed or entirely eliminated, if desired.

In Fig. 4 I have shown a slightly modified form of the invention wherein a three-heat arrangement of coils is provided, the 95 device being otherwise, in structure, the same as the form just described. In this form, the insulating base 3' is provided with eight grooves 4' as in the other form which communicate with the front and rear 100 channels 5' and 6' respectively and mounted in the groove or channel 5' are the two contact strips 18 and 19, the ends of which align respectively with the first two grooves and the central two grooves 4'. Mounted in 105 the channel 6' are the additional contact strips 20 and 21, the ends of which respectively align with the second, third, sixth and seventh channels or grooves 4' of the base. Mounted on the under face of the base 110 3', at the end thereof having the channel 6' therein are a pair of contact strips or plates

22 and 23, the ends of the former alining with the planes of the first and fourth channels, while the ends of the latter aline with the planes of the fifth and eighth channels. 5 Heating coils are of course disposed in each of the channels or grooves 4' and the coil in the first channel is connected with the plate 18 and one end of the strip 22, while the coil in the second channel connects the opposite end of the strip 18 with one end of the strip 20. The coil in the third channel connects the opposite end of the strip 20 with one end of an additional strip 24 mounted on the under face of the base 3' at 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570

15 the end having the channel 5' therein, while the coils in the two central channels connect the ends of the strip 19 with the inner opposed ends of the strips 22 and 23. The coil in the sixth channel connects the opposite end of the strip 24 with one end of the strip 21 and the coil in the seventh channel connects the opposite end of the strip 21 with an additional contact plate 25 in the channel 5'. The coil in the last and eighth channel connects the one end of the strip 23 with a still further contact plate 26 in the channel 5' and wires 27 and 28 which lead respectively from said plates 25 and 26 connect with a pair of terminals 29 and 30 respectively. An additional terminal 31 mounted in the forward end of the base in alinement with the aforesaid terminals connects by means of a wire 32 to the strip 18. A flexible cord 33 carried on the central terminal 29 carries a porcelain plug 34 which may be connected with the terminal 31 to allow the maximum heat to be obtained through the circuits 29 and 30. From this description of the circuits in this form, it is obvious whereby the heat in this device may be varied.

From the foregoing it will be seen that I have provided a simple electric heater and while I have particularly described the elements most well adapted to perform the functions set forth, it is obvious that various changes in form, proportion and in the minor details of construction may be resorted to without departing from the spirit or sacrificing any of the principles of the invention.

Having thus described this invention, what is claimed is:—

1. A heating device of the class described, comprising a metallic frame supported on legs, a plastic body mounted in said base, said body being provided with a plurality of parallel channels adapted to receive heating elements therein, heating coils disposed

in the channels of said base, means connecting said coils to dispose the same in circuit with one another, terminals mounted in said base and having portions thereof projecting beyond one face of the frame, said terminals being arranged in circuit with said heating coils, and a grid plate removably mounted on the upper face of said frame, the slots of said plate alining with the channels in said plastic body.

2. A device of the class described comprising a metallic frame, a composition body mounted therein, the upper face of which is provided with a plurality of longitudinal channels and also provided with a pair of transverse channels communicating with the aforesaid channels and disposed at the front and rear ends of the latter respectively, a plurality of heating coils disposed in said longitudinal channels, a plurality of connecting plates disposed in said transverse channels and engaged with the ends of said heating coils to arrange the same in circuit with one another, a plurality of terminals mounted in said body and having connection with certain of said connecting plates, and a grid plate removably applied to said frame, the slots thereof alining with and of a length equal to the longitudinal channels of said body.

3. A device of the class described comprising a metallic frame, a composition body mounted therein, the upper face of which is provided with a plurality of longitudinal channels spaced at regular intervals for the greater portion of the width thereof, and also having a pair of transverse channels communicating with said longitudinal channels at the front and rear ends thereof, heating coils disposed in said longitudinal channels, a plurality of connecting plates secured in said transverse channels, said plates being arranged at the ends of the alternate partitions formed by the provision of said longitudinal channels, and each plate being designed to extend across a pair of adjacent channels to connect the respective heating coils therein, a plurality of terminals mounted in said body and having connection with said heating coils, and a grid plate removably applied to the upper face of said frame.

In testimony whereof I hereunto affix my signature in the presence of two witnesses.

ALBERT W. PERSON.
